UNITED STATES PATENT OFFICE.

OTTO ALWIN SCHMIDT, OF CHELMSFORD, ENGLAND, ASSIGNOR TO THE HOFFMANN MANUFACTURING COMPANY LIMITED, OF LONDON, ENGLAND.

MACHINE FOR GRINDING ROLLERS.

1,055,807.

Specification of Letters Patent. Patented Mar. 11, 1913.

Application filed February 16, 1912. Serial No. 678,016.

To all whom it may concern:

Be it known that I, OTTO ALWIN SCHMIDT, a subject of the German Emperor, residing at Chelmsford, in the county of Essex, England, have invented a certain new and useful Improvement in Machines for Grinding Rollers, of which the following is a specification.

This invention consists of a machine or device for grinding or facing at right angles to their length one or both ends of rollers such as those employed in roller bearings by the action of a moving grinding member or members upon one or both ends of such rollers while they are moving through a guide or holder.

According to some forms of the invention the machine may comprise one or more movable grinding members arranged either vertically or horizontally to act on one or simultaneously on both ends of the rollers and a holder or holders, guide or guides, adapted to freely hold and present the ends of the rollers to the face or faces of a grinding member or members in a path which preferably differs in direction to the directed movement of the grinding member or members and in which holder, or holders, guide, or guides, the rollers preferably have more or less of a traveling rolling motion and further in which if desired a hopper or hoppers or mixing device or devices may be arranged so that the rollers are mixed at some point of their travel, or in which means may be provided for passing the rollers out of contact with the grinding member or members and into contact with same again along a different path.

A machine constructed to illustrate by way of example some of the features of the invention is shown in the accompanying drawing, in which:—

Figure 1 is a part longitudinal elevation, a portion being in section on line $y-y$, Fig. 3; Fig. 2 is a plan; and Fig. 3 is a cross section on line $x-x$ of Fig. 1.

The machine illustrated comprises two oppositely facing rotatable disks 1, 2, carried by a fixed horizontal shaft 3 which disks are driven in the same direction from gear wheels 4, 5, by the pinions 6, 7, on a driven shaft 8. The right hand support for the shafts is not shown nor is a screw adjustment for the disk 2 which enables it to be moved to and from the disk 1 when the faces

of the disks require attention or for other purposes. The two disks may be of abrasive material or of other material which is capable with the addition of suitable abrasive material of effecting the grinding and one of the disks such as 1 has a spring such as 9 so that when the disk 2 is screwed up, a spring pressure on the rollers between the two disks is obtained the means of adjustment and of obtaining pressure being similar to those employed in ball grinding machines having vertical grinding disks of a somewhat similar type.

Between the two disks is interposed a holder or guide arranged eccentrically to the axis of the grinding member and which holder comprises two concentric parts or rings 10, 11, one being fixed and the other floating. Between these the rollers 12 to be faced can have more or less of a rolling movement of progression and beyond the edges of which the ends of such rollers can project sufficiently to touch the grinding disks. To assist in strengthening the part or ring 10 and to afford means for securing it, a web 10^b is provided which has a thickened portion 10^c for attachment to a bracket 13 capable of being slid in grooves 14 on the base plate 15 when the part or ring 10 is to be moved to allow for the wear of the grinding disks or for other purposes such as for facing the grinding disks. The ring 11 is rotatable on an eccentric disk 16 made a sliding fit on the shaft 3 and prevented from rotating thereon by the key 3^a in a suitable collar or hub 17, the rotation of the disk 11 being assisted by balls 18 located between two curved tracks on the outside and inside faces of the parts 16 and 11, respectively.

The holder part or ring 10 has a gap 95 therein and its two ends thus formed are extended outside of the effective grinding range of the disks 1, 2, as shown at 10^a to facilitate the entrance of the rollers between the disks and also the discharge of same 100 therefrom.

On the upper or discharging side, the rollers pass under the part 10^a onto a track 19 held between two side plates 20, 20, and from track 19 they fall upon a lower track 21 also held between the plates 20, 20, from which they run down to the entering point between the disks. The walls 20, 20, and tracks 19, 21, thus provide a hopper or mixing device of the same width as the rollers 110

so that while they can mix in progressive order they cannot twist or get askew. Such hopper affords a means of charging and discharging the rollers, exposing them for 5 gaging purposes or inspection, and obtaining by the mixing, uniformity.

In operation it will be seen that the end faces of the rollers traveling eccentrically to the grinding disks will be acted upon by 10 such disks by reason of the rollers projecting on each side from the holder 10, 11; and that they may have any desired number of passes through the machine, their travel which is in the nature of a rolling or partly rolling 15 motion being obtained by the eccentric position of the disks with relation to the holder and by the assistance of the loosely rotating part of such holder.

The machine may be combined with one 20 for grinding the peripheries of the rollers and through which they travel with a similar rolling motion. Modifications may be made in same, for example, the disks need not be co-axial as shown, and in such case 25 the holder need not be eccentric or one disk or grinding member only to act on one end face only may be employed, or other changes in form may be made, the machine illustrated being an embodiment of a means for 30 grinding the end faces of rollers while having a traveling rolling or partial traveling rolling motion.

What I claim is:—

1. A machine for facing at right angles to 35 their length the ends of a series of rollers, comprising in combination a framework, a holder in which the rollers are accurately but freely held and capable of a traveling rolling motion, and a grinding member to 40 which an end of each of said rollers is presented by the holder.

2. A machine for facing at right angles to 45 their length the ends of a series of rollers, comprising, in combination, a framework, a holder provided with a channel in which the rollers are accurately but freely held and capable of a traveling rolling motion and grinding members to which each end of such rollers is presented during their travel.

50 3. A machine for facing at right angles to their length an end of each of a series of rollers, comprising, in combination, a framework, a holder provided with a channel in which the rollers are accurately but freely held and capable of a traveling rolling motion, and movable grinding disks to which each end of such rollers are presented during 55 their travel, such channel being located eccentrically with respect to the grinding disk 60 so as to cause the latter to effect the traveling rolling movement of the rollers.

4. A machine for facing at right angles to

their length an end of each of a series of rollers, comprising, in combination, a framework, an in part circular holder in which the rollers are accurately but freely held and capable of moving with a traveling rolling motion, and a movable grinding disk to 65 which the ends of such rollers are presented by the holder during their travel, such disk 70 being located eccentrically to the holder and said holder having a gap therein with entering and discharging points for the rollers the location of the disk with respect to the holder acting to take the rollers into the 75 holder from the entering point and discharge them at the discharging point.

5. A machine for facing at right angles to 80 their length an end of each of a series of rollers, comprising, in combination, a framework, a holder in which the rollers are accurately but freely held and capable of rolling, a movable grinding member to which the ends of such rollers are presented by the holder, and a mixing device for the rollers, 85 interposed in the path of travel of same.

6. In a machine for facing at right angles to their length an end of each of a series of rollers, a holder for the rollers comprising two concentric rings one of which is fixed 90 and the other floating, and from the side of which the ends of the rollers project and a movable grinding disk having a flat face adapted to act on the ends of such rollers.

7. In a machine for facing at right angles 95 to their length an end of each of a series of rollers a holder comprising two concentric rings one of which is fixed and the other floating the rollers being located in a space between such rings so that while accurately 100 guided one end projects, a disk on which the floating ring is carried, balls located between the floating ring and disk, and movable grinding means adapted to act on the ends of the rollers.

105 8. In a machine for facing at right angles to their length an end of a series of rollers, a holder for the rollers comprising two concentric rings, one of which is fixed and the other floating, and from the side of which 110 the ends of the rollers project one of said rings having a gap therein, a hopper with which such gap connects and into which the rollers are discharged and from which they can re-enter the holder, and a movable 115 grinding member adapted to act on the ends of the rollers.

In testimony whereof I have hereunto set my hand in the presence of two subscribing witnesses.

OTTO ALWIN SCHMIDT.
